UNITED STATES PATENT OFFICE.

ARNOLD BINDER, OF CHICAGO, ILLINOIS.

CHAIR.

Application filed March 12, 1923. Serial No. 624,472.

To all whom it may concern:

Be it known that I, ARNOLD BINDER, a citizen of the United States, and a resident of the city of Chicago, county of Cook, and 5 State of Illinois, have invented certain new and useful Improvements in Chairs, of which the following is a specification.

My invention relates to novel improvements in chairs, and has for its principal object the provision of an improved construction of this character which will be economical in manufacture.

Among other objects of the invention is the provision of a chair, the construction of 15 which is such that will permit the chair to be collapsed when not in use.

Other objects will appear hereinafter.

The invention consists in the combinations and arrangements of parts hereinafter described and claimed.

The invention will be best understood by reference to the accompanying drawings forming a part of this specification, and in which,

25 Fig. 1, is a front elevational view of a chair embodying the invention;

Fig. 2, is a sectional view taken substantially on line 2—2 of Fig. 3;

Fig. 3 is a sectional view taken substantially on line 3—3 of Fig. 1;

Fig. 3^a is a sectional view taken substantially on line 3^a—3^a of Fig. 2; and

Fig. 4, is a sectional view taken substantially on line 4—4 of Fig. 1.

35 Referring to the drawings showing the preferred form of construction, 10 indicates the arm rests of the chair A, 11 indicates the bases or feet of the chair. The back of the chair is indicated at 12, and as illustrated in 40 the drawings, is provided with an opening through which a stud 14 formed on one of the arm rests is taken and which passes into a socket 15 formed in a cap 16 (Fig. 3). The chair back is also provided with a slot 45 17 opposite the hole 13 for the reception of a stud 18 formed on the other arm rest 10 and adapted to pass into a socket 19 formed in a cap 20 (Fig. 3^a). By this construction it is apparent that the back 12 can be swung 50 in a direction to disengage the slot 17 from the stud 18 for purposes to be more fully hereinafter understood.

The arm rests 10 and the bases 11 are provided with equally spaced apart sockets as indicated at 20, Fig. 3. The sides 21 of the

chair A include a plurality of balusters indicated at 22, Fig. 1, provided with reduced portions 23 adapted to pass into the sockets 20 and fixed therein by means usually employed in the furniture art. The balusters 22 are curved as shown and cross each other at a point indicated at 24, Fig. 1, and are pivotally connected together at such point by a rod member 25 having nuts 26 screw-threaded on its end opposite its head thereof. The seat of the chair is indicated at 27 and includes a number of slats 28 pivotally connected together at 29 by a transverse rod member 30 having nuts 31 screw-threaded on one end thereof. The slats 28 are alternately pivotally connected at their ends 32 to the balusters 22 by rod members 33 each provided with nuts 34 screw-threaded on one end thereof. The free ends indicated at 35 of the slats are bevelled inwardly and 70 downwardly as at 36 and are shaped to conform to the adjacent curved sides 37 of the balusters 22 on which the free end of the slats rest when the chair is in distended position.

When the chair is in distended position, as illustrated in Fig. 1, it will be apparent that the back 12 serves to lock the chair in such distended position, and to collapse the chair, all that is necessary to be done is to swing the back so as to disengage the slot 17 from the stud 18, the chair being shown partially collapsed by dotted lines in Fig. 1.

It is intended that the slats 28 be arranged side to side in close proximity so as 90 not to provide spaces therebetween but to form as near as possible a continuous seating surface, as best illustrated in Fig. 4.

From the above description it will be seen that the construction of my chair is economical in manufacture and while the drawings illustrate the preferred form of curvature of the balusters, this may be changed according to desire without destroying the utility of the invention.

100 While I have illustrated and described the preferred form of construction for carrying my invention into effect, this is capable of variation and modification without departing from the spirit of the invention. 105 I, therefore, do not wish to be limited to the precise details of construction set forth, but desire to avail myself of such variations and modifications as come within the scope of the appended claims.

Having described my invention, what I claim as new and desire to secure by Letters Patent is:

1. A chair structure of the class described comprising supports including a plurality of balusters pivotally connected together and crossing each other at the pivot connection, a collapsible seat carried by the supports including a plurality of slats pivotally connected together and alternately pivotally connected to the balusters, and a panel-like backing member swingably mounted on said supports and adapted to lock the supports in distended position.
- 15 2. A chair structure of the class described comprising supports including a plurality of balusters pivotally connected together and crossing each other at the pivot connection, a collapsible seat carried by the supports including a plurality of slats pivotally connected together and alternately pivotally connected to the balusters, and a back pivotally carried by the supports and adapted to lock the supports in distended position.
- 25 3. A collapsible chair structure including arm rests, bases, sides including balusters pivotally connected together and having their ends fixed to the arm rests and bases, and a collapsible seat including members pivotally connected together and alternately pivoted to the balusters and having their

free ends bevelled and resting on the adjacent baluster.

4. A collapsible chair structure including 35 arm rests, bases, sides including balusters pivotally connected together and having their ends fixed to the arm rests and bases, a collapsible seat including members pivotally connected together and alternately 40 pivoted to the balusters and having their free ends bevelled and resting on the adjacent baluster, and a back pivotally carried by one of the arm rests and provided with a slot opposite the pivoted connection, there 45 being a stud on the other of the arm rests adapted to pass into the slot.

5. A collapsible chair structure including 50 arm rests, bases, sides including balusters pivotally connected together and having 55 their ends fixed to the arm rests and bases, a collapsible seat including members pivotally connected together and alternately pivoted to the balusters and having their free ends bevelled and resting on the adjacent baluster, and a back rest adapted to lock the chair parts in distended position.

In testimony whereof I have signed my name to this specification in the presence of two subscribing witnesses.

ARNOLD BINDER.
